VENTILATED CONTAINER FOR AIR FRESHENER

Frank J. Curran, 3250 S. Highland Ave.
Downers Grove, Ill. 60515

Filed Mar. 10, 1972, Ser. No. 233,863

Term of patent 14 years

Int. Cl. D23—04

U.S. Cl. D23—150

FIG. 1.

FIG. 3.

FIG. 2.

FIG. 1 is a general perspective view of the ventilated container for air freshener showing my new design;

FIG. 2 is a side elevational view of the ventilated container for air freshener; and

FIG. 3 is a top plan view of the ventilated container for air freshener. A bottom view of the ventilated container for air freshener would be similar to the illustration shown in FIG. 3.

The broken lines are shown in FIGS. 1, 2 and 3 for illustrative purposes only.

I claim:

The ornamental design for a ventilated container for air freshener, substantially as shown and described.
